(57) **CLAIM**

I claim the ornamental design for an add-on tote for a walker, as shown and described.

DESCRIPTION

FIG. 1 is a perspective view of an add-on tote for a walker showing my new design;

FIG. 2 is a top plan view thereof;

FIG. 3 is a bottom plan view thereof.

FIG. 4 is a front elevational view thereof;

FIG. 5 is a rear elevational view thereof; and

FIG. 6 is a right side elevational view thereof, the left side elevational view being a mirror image thereof; and,

FIG. 7 is a reduced perspective view showing the add-on tote for a walker in use; the broken lines depict environmental structure for illustrative purposes only and form no part of the claimed design.

The broken line showing in FIGS. 1, 4, 5, and 6 is included for the purpose of illustrating stitching on the claimed design.
